UNITED STATES PATENT OFFICE.

MICHAEL H. LONG, OF CHICAGO, ILLINOIS, ASSIGNEE OF ONE-HALF TO MORGAN K. BARNUM, OF LA GRANGE, ILLINOIS.

EMERGENCY-KNUCKLE FOR CAR-COUPINGS.

1,099,506.

Specification of Letters Patent.

Patented June 9, 1914.

Application filed August 14, 1912. Serial No. 714,962.

To all whom it may concern:

Be it known that I, MICHAEL H. LONG, citizen of the United States, residing at Chicago, in the county of Cook and State 5 of Illinois, have invented a certain new and useful Improvement in Emergency-Knuckles for Car-Couplings, of which the following is a full, clear, concise, and exact description.

10 My invention relates to an emergency-knuckle for car-couplings.

One of its objects is to provide a knuckle adapted to fit the draw-bar of any of the Master Car-Builders' type of couplers.

15 Another object of my invention is to provide an improved emergency-knuckle which, when used to replace a standard knuckle, will hold the parts of the coupler in their usual positions, and thus provide the usual 20 clearance space between the ends of the car.

My invention thereby overcomes one of the chief objections to the type of emergency-knuckles in common use in which there is too much slack provided between the coupled 25 ears, rendering it dangerous to pass from one car to the other. My invention, moreover, in providing means for holding the draw-heads in the usual relative positions, makes it possible to couple up the air-brake 30 hose without the use of an extension or dummy hose.

Another object of my invention is to provide a knuckle which can quickly and readily be substituted for the knuckle of the 35 Master Car-Builders' type of coupler, and which, when so substituted, permits the coupling to be made from one side of the car in the usual manner without necessitating the brakeman going between the cars to effect the coupling.

A further object of my invention is to provide an emergency-knuckle of simple construction, light in weight, and which requires no tools in its application.

45 My invention consists of a knuckle in which the usual tail piece is omitted and in which a rib is provided on the side of the supporting lug approximately opposite to the knuckle-head, such rib being adapted 50 to engage with the transversely extending forward end or edge of the side wall of the coupler head and thus to hold the knuckle against rotation. Except for the omission of the tail piece and the provision of said

rib, the knuckle may be of the usual configuration.

My invention may be more readily understood by reference to the accompanying drawings, in which—

Figure 1 is a plan view of two intercoupled couplers, one of which is provided with the usual knuckle, and the other of which is provided with the emergency-knuckle of my invention, one of the supporting ears of the coupler head being broken away to more 65 fully disclose the invention; and Fig. 2 is a perspective view of the knuckle of my invention.

Similar letters of reference refer to similar parts in both of the figures of the drawings.

The coupler head 1 is shown as provided with a knuckle 2 pivoted between the ears 3 of the draw-bar in the usual manner. This knuckle, being of a common, well-known 75 construction, requires no further description of its mode of attachment and operation. The similar draw-bar 4 is shown as having my emergency-knuckle pivoted between the ears 5 thereof. Such knuckle comprises a 80 knuckle-head 6, a supporting lug 7 adapted to fit between the ears 5 of the coupler head and provided with an opening for receiving the pin 8 by which the knuckle is attached to the draw-head. The side of the supporting lug approximately opposite the knuckle-head 6 is provided with a rib or shoulder 9 which, when the knuckle is secured in place, abuts against the forward end 10 of the side wall of the coupler head on the knuckle 90 side thereof and thus holds the knuckle against rotation. It will be observed that the emergency-knuckle is not provided with the usual tail piece. The side of the supporting lug from which said tail piece normally projects may be somewhat thickened as at 11 in order to strengthen the knuckle. 95

It will thus be observed that the emergency-knuckle of my invention is, by reason of its very structure, securely and rigidly 100 held in place without the help and irrespective of the usual locking device; and it will also be observed that my emergency knuckle, being designed to be locked against outward rotation by engaging a wall of the coupler 105 head within the perimeter or horizontally projected area of the head, need have no parts extending outside of the Master Car

Builders' standard contour lines for car couplers, thus permitting a coupler employing my emergency knuckle to effect a coupling with any other coupler whose contour lines conform to the Master Car Builders' standards. In case, therefore, one of the knuckles in ordinary use becomes broken, or in case the locking device therefor becomes ineffective, such ordinary knuckle can be replaced 10 moved and my emergency-knuckle substituted therefor without regard to the locking device, it being necessary merely to drop the pin 8 through the aligned openings in the ears of the draw-head and the supporting lug of 15 the emergency-knuckle. Since it is necessary, in order to couple two cars together, to have only one of the knuckles rotate upon its pivot, the locking device for the knuckle 2 of the opposite coupler can be operated to 20 permit of the knuckle 2 coupling with the knuckle-head 6 in the usual manner. It is thus possible to couple the two cars together in precisely the same manner as is usually done, that is from the side of the cars and 25 when the cars are so coupled, they are held with the usual amount of clearance between them.

My emergency-knuckle, unlike others in common use, will fit any Master Car Builders' vertical type of draw-bar. My emergency knuckle, unlike others in common use, can be applied without removing the locking device in the bar. Furthermore, other types of emergency knuckles in common use hold 30 the cars so far apart that the air-brake hose cannot be coupled without the use of extension hose and moreover the cars are set so far apart that it is dangerous to pass from one car to the other. In contradistinction 35 thereto my emergency-knuckle holds the cars the usual distance apart.

I claim:

1. An emergency knuckle for car couplers

of the type indicated, said knuckle being provided with a supporting lug which is adapted to be secured between the ears of a coupler-head, and being formed with a shoulder which is adapted to engage the forward transversely extending end of the side wall of the coupler-head between said ears, to thereby maintain said knuckle in closed relation with the coupler-head and prevent outward rotation of said knuckle. 45 50

2. An emergency knuckle for car couplers of the type indicated, said knuckle being provided with means whereby it may be secured to a coupler-head that is provided with ears for receiving a pivot pin, and being also provided with laterally projecting means integrally attached thereto and adapted to engage the forward transversely extending end of the side wall of a coupler-head between the pivot pin ears thereof, to thereby prevent said knuckle from turning outwardly 60 65 to open position.

3. An emergency knuckle for car couplers of the type indicated, said knuckle being provided with a portion adapted to be connected to a coupler-head, and being also adapted to engage the coupler-head to prevent vertical movement of the knuckle, and said knuckle being also formed with a face which is adapted to engage a wall of the coupler-head on the knuckle side thereof to prevent said knuckle from rotating outwardly to open position, said face being adapted to engage said wall of the coupler-head within the horizontal projection of the coupler-head. 70 75

In witness whereof, I, hereunto subscribe my name this second day of August, A. D., 1912.

MICHAEL H. LONG
